5 Claims. (Cl. 196—63)

The present invention relates to improvements in the heating up of carbonaceous materials.

The drawing is diagrammatic in form and illustrates a method by which the present invention 5 may be carried into practice.

The destructive hydrogenation of carbonaceous materials of the nature of coals, tars, mineral oils and the like usually proceeds with considerable evolution of heat. From a certain size of 10 plant upwards, the heat set free is greater than the heat losses, the latter being composed of two parts namely radiation losses which are dependent on the surface area of the apparatus and the temperature of the radiating surfaces, and 15 losses in the heat-exchanger employed in the usual manner for imparting the heat of the reaction products to the initial materials because the products issuing from the heat-exchanger always carry away a certain amount of heat in 20 practice. All these losses can be reduced to a minimum, but in spite of this it is still necessary to supply heat from outside to plants of medium size and it is only with quite large units that the 25 heat of reaction preponderates. Even in this case, the whole plant must first be brought to the operating temperature. The time necessary for this purpose depends on the mass of iron to be brought to operating temperatures, the strength 30 of the available source of energy and the radiation of the preheating system.

In the prior heating arrangements, the necessary heat has usually been supplied to the initial materials in tubular preheating apparatus which is heated by gas or fed from a source of electric 35 current.

The drawbacks of such a heating up are as follows:—

(1) The naturally high speed of the initial material in the preheater which is necessary for the 40 transference of heat causes a loss in pressure which must be continuously obviated by the gas circulation pump. If the heating up of the initial materials takes place in a preheater in front of the reaction chamber, it is impossible to avoid 45 the pressure prevailing in the reaction chamber from being lower than the pressure set up by the pump to an extent corresponding to the resistance of this preheater.

(2) The preheater is very expensive in operation 50 because in the case of gas-heated preheaters the degree of thermal efficiency is usually very bad by reason of the high temperatures (as for example more than 400° C.) and electrical energy on the other hand is not cheap.

55 Very frequently, especially when the reaction

itself proceeds with great evolution of heat, the preheater has only to serve the single purpose of bringing the whole system at the beginning of the operation to the necessary temperature. When the reaction has been initiated, the preheater then usually is idle since the heat regeneration by means of the heat-exchanger brings the initial materials to a sufficiently high temperature but the preheater still consumes heat and fails in 10 pressure. If, by means of a by-pass, the preheater is short-circuited, there is then the danger that the residues of products remaining in the tubes will coke and render the preheater useless.

(3) Most preheaters, whether heated by gas, 15 electricity or otherwise, transfer the heat to be supplied through a relatively small surface for the reasons already mentioned. The outer film of the initial materials which transfers the heat to the inner parts of the materials is therefore usually at a higher temperature than is desirable 20 for the initial materials, and even if overheating can be reduced by employing special precautions, such as regulating the supply of heat, ribbed tubes of different circuits, there still remain the said 25 drawbacks of pressure difference and bad degree of efficiency. Even by heating one of the initial materials, as for example the gas, and then mixing it with the colder initial material in order to produce the desired reaction temperature, a temporary marked exceeding of the initial 30 reaction temperature desired to be set up cannot always be avoided in practice because the equalization of the mixture proceeds in wave-like fluctuations in temperature. This is also true in the case when the necessary heat is supplied by an 35 additional exothermic reaction, as for example of the reaction $CO + 3H_2 = CH_4 + H_2O$.

We have now found that the said drawbacks are avoided by directly or indirectly supplying to the still hot products having left the reaction chamber further heat, by means of a medium heated outside the system, advantageously by means of a vaporized normally liquid medium having a high heat of vaporization, preferably a heat of vaporization of at least 500 kilocalories per kilogram the initial materials flowing towards the reaction chamber being heated by means of the products thus heated. The said heating medium cannot only be brought into indirect heat exchange relation with the reaction products as 50 soon as the latter leave the reaction chamber but also some time after their issue from this chamber provided the said reaction products are still in heat-exchange relation with the initial materials to be heated.

When the supply of heat is effected by means of a liquid, the latter is preferably heated outside the system by any of the known methods in a separate heating device, preferably a heating device simultaneously used for several systems. The burden of the resistance of this heating device does not fall on the system and moreover it is very small. Furthermore, only a small expenditure of energy is necessary for heating, especially as compared with a preheater arranged in circulation.

The heating device for the heating medium works at a very high degree of efficiency because its inlet temperature is low. Since the heat supplied, for example when using water as the heating medium, is utilized for the greater part as heat of vaporization, the heat of condensation supplied in the regeneration increases the degree of efficiency of the latter very considerably.

Not only water, but also other media may be employed as heating media, as for example oils or gases. It is especially advantageous, however, to employ condensing steam because it has very good heat-transferring properties and the heat transit value of the regeneration surfaces is increased to no small extent. Care should always be taken not to supply to the effluent substances so much heat that injurious overheating takes place.

The thermal reaction may be initiated by heating the first charge of initial material by pre-heaters preheated with gas. The further charges of initial material are then heated according to the present invention.

The process according to this invention allows of an easy adjustment of the supply of heat by regulation of the amount or temperature of the heating medium or both. It offers further greater advantages, for example, when working in the so-called sump phase, that is the phase in which the initial materials are present either as a liquid or as a pasty dispersion of solids in liquids, for example in the destructive hydrogenation of coals even when in the separator directly attached to the reaction chamber large amounts of liquid products are obtained the heat content of which is lost as far as the regeneration is concerned because these products are usually further worked up at the temperature which they have in the separator, since in such case the remaining vaporous constituents, if not further heated, do not contain amounts of heat sufficient for heating by regeneration the initial materials substantially to the reaction temperature.

A further advantage of the operation according to the present invention consists in the fact that the heating medium need not be brought into heat exchange with the products having left the reaction space at a place at which these products have the highest temperature; thus, for example, if three heat regenerators arranged in series are employed the said heating medium may also be brought into heat exchange with the products passing through the second heat regenerator. In this case the heating medium need not be brought to a temperature as high as is necessary when bringing it into heat exchange with the products directly after their issue from the reaction space and nevertheless the necessary amount of heat is imparted to the products.

The said kind of preheating may also be used with special advantage for setting apparatus in operation. The initial material is thereby pre-heated in a cautious manner by heat exchange with the material leaving the reaction chamber

and which latter material at first is still cold, the said chamber thus being slowly heated up by means of a medium outside the system. It has the advantage that especially with an exothermic course of the reaction the supply of heat can be readily interrupted when the operation requires it; when working with the usual preheaters this is practically impossible in a satisfactory manner as already pointed out.

Example

20 tons per hour of a tar are pumped together with 30,000 cubic meters per hour of hydrogen through two heat regenerators arranged in series and are then introduced while at the reaction temperature of 425° C. into the first of two reaction vessels; they leave the second vessel while at 450° C. From the adjacent separator two tons per hour of high boiling constituents are removed. To the mixture of vapors and gases leaving the separator 1 ton of steam superheated to 450° C. and maintained under superatmospheric pressure is then supplied before its entrance into the heat regenerators, the initial materials being in heat-exchange with the said mixture of vapors and gases thus being heated to 425° C. before entering the first reaction vessel. Without the said operation a preheater would be necessary for the complete heating up to the reaction temperature which supplies the still lacking heat amounting to about 600,000 kilocalories per hour.

The process according to the present invention is not only applicable to all varieties of destructive hydrogenation as for example aromatization, hydrofining or the usual splitting hydrogenation under pressure; but also with other heat treatments of carbonaceous materials in the presence or absence of hydrogen or steam or other gases, such as cracking or non-splitting hydrogenation, the necessary heat may be supplied with advantage in the aforescribed manner.

The foregoing example further illustrates the nature of this invention but the invention is not restricted to this example.

In the drawing numeral 1 designates the feed line by which the hydrocarbon material to be hydrogenated is fed. Pump 2 forces the material through the line 3 and through heat exchangers 4 and 5. Hydrogen is forced into the line 3 by pipe 6. From the heat exchangers the heated mixture of hydrogen and hydrocarbon passes by a line 7 into the reaction vessels 8 and 9 which are shown in series. These vessels are adapted to withstand the high pressure and temperature required for the reaction and the reacted materials flow through a valved line 10 into a separator 11, from which any unvaporized material may be removed by a pipe 12. The vaporized materials pass through a pipe 13. If desired, a portion of the material from the second reaction vessel 9 may be passed directly into the pipe 13 by a valved pipe 14. Steam at high temperature and pressure is also passed into the line 13 by means of a pipe 15 and the mixture of the reaction product and steam then passes through the heat exchangers 5 and 4, in the order mentioned, by the pipes 16 and 17 and issues from the pipe 18 into a separator 19. The liquefied products are taken from the separator by a pipe 20 and gas by a pipe 21.

What we claim is:—

1. In the thermal conversion of distillable carbonaceous materials in one or more reactors the step of heating up the initial carbonaceous materials to the temperature required for the said

- thermal conversion by indirect heat exchange relation with at least part of a prior charge of still hot reactants to which after issue from the last reactor a higher temperature has been imparted than they had in the said conversion, by a medium which has been heated by a foreign source of heat to a higher temperature than these reactants have at the place at which the said medium is supplied.
- 5 2. In the process as claimed in claim 1 supplying to the still hot distillable carbonaceous materials having undergone the thermal conversion a vaporized normally liquid medium having a high heat of vaporization.
- 10 3. In the process as claimed in claim 1 supplying superheated steam to the still hot distillable carbonaceous materials having undergone the thermal conversion.

4. In the process as claimed in claim 1 adjusting the temperature desired for the thermal conversion by supplying regulated amounts of heating medium and regulating the temperature of this heating medium.

5 5. In the process as claimed in claim 1 heating up the initial carbonaceous materials by indirect heat exchange relation with the constituents of the still hot reactants issuing as vapors from the last reactor and to which a higher temperature than they have in the conversion has been imparted by a foreign source of heat.
